Fig 9 Fig 10Fig 10

FIG. 1 is a front elevational view of our heater cabinet;
 FIG. 2 is a side elevational view showing the left side of the heater cabinet, the right side being identical to the one shown;

FIG. 3 is a rear elevational view of the heater cabinet;
 FIG. 4 is a top plan view of the heater cabinet;

FIG. 5 is a fragmental vertical sectional view taken generally along line 5-5 of FIG. 1;

FIG. 6 is a fragmental horizontal sectional view taken generally along line 6-6 of FIG. 1;

FIG. 7 is a fragmental vertical sectional view taken generally along line 7-7 of FIG. 2;

FIG. 8 is a fragmental horizontal sectional view taken generally along line 8-8 of FIG. 4;

FIG. 9 is a front elevational view showing another embodiment of the heater cabinet;

FIG. 10 is a fragmental vertical sectional view taken generally along line 10-10 of FIG. 9;

FIG. 11 is a fragmental horizontal sectional view taken generally along line 11-11 of FIG. 9.

This is a continuation of design applications Ser. No. D. 84,702, filed Oct. 11, 1965, and Ser. No. D. 87,388, filed Oct. 11, 1965, both abandoned.

We claim:

The ornamental design for a heater cabinet, as shown and described.
